UNITED STATES PATENT OFFICE.

JOHN G. POWELL, OF PHILADELPHIA, PENNSYLVANIA, ASSIGNOR OF ONE-HALF TO EDWARD POWELL, OF SAME PLACE.

KNIT FABRIC.

SPECIFICATION forming part of Letters Patent No. 653,398, dated July 10, 1900.
Application filed November 24, 1899. Serial No. 738,123. (No specimens.)

To all whom it may concern:

Be it known that I, JOHN G. POWELL, of Philadelphia, in the State of Pennsylvania, have invented certain new and useful Improvements in Stockings, whereof the following is a specification, reference being had to the accompanying drawings.

In said drawings, Figure 1 represents a stocking formed of a fabric made in accordance with my invention, while Figs. 2 and 3 are detail views, upon an enlarged scale, illustrating the structure of the web at those portions where prominent characteristics occur.

In the manufacture of stockings it is often considered desirable to knit one portion of the foot with a yarn differing in color or in weight or in both particulars from that used for the other portion of the foot, the articles thus made being termed "split-foot stockings." One method for the production of such stockings—viz., that set forth in Letters Patent of the United States No. 460,037, dated September 22, 1891—results in a fabric which is a two-part structure throughout—that is to say, in order to make the upper and lower halves of the foot from different yarns two independently-knit webs are formed, and these are united along their proximate edges by interknitting. This method was, however, necessarily followed throughout the whole article, so that the seam or line of demarcation between the two webs was manifest, not only where they were formed of different yarns, (as in the foot of the stocking,) but also where the same yarn was used for both webs, as in the leg portion. Such stockings were therefore characterized by a lack of finish or imperfection in the leg portion, since the line of union of the two webs in the leg presented the appearance of a seam or partial cord as distinguished from an uninterrupted and uniform fabric. In my application for Letters Patent filed April 21, 1899, Serial No. 713,891, I have specified and shown a method of manufacture which avoids this difficulty and accomplishes the formation of two independently-knit webs throughout any desired portion and their union by interknitting, while it permits the merging of such independent webs into a continuous tubular web throughout the remainder of the stock-

ing. I have since discovered that a fabric structurally different from that set forth in my said application can be produced upon machines of the same general character as 55 were there contemplated and that an article, such as a stocking, made from such new fabric possesses very desirable characteristics. This new fabric and the method of its embodiment in a stocking I will now proceed to describe.

I prefer to employ a machine of the general type shown in my Letters Patent No. 582,547, dated May 11, 1897, which comprises two flat needle-beds disposed at an angle to each other 65 and having a reciprocating carriage which actuates the needles and feeds the yarn to them. This carriage is capable of alternative methods of operation—that is to say, it may actuate the needles of one bed alone by a complete reciprocation back and forth upon that side and may then perform a similar function upon the needles of the other bed alone, or in making a complete reciprocation it may 70 actuate the needles of one bed on its outgoing movement and the needles of the other bed upon its return movement. The two independently-knit webs desired in the foot portion of the stocking can obviously be formed upon such a machine and can, as 75 described in my said application, Serial No. 713,891, be united by interknitting along their proximate edges, such interknitting being effected by throwing over a needle from that bed which for the time being is idle and engaging a loop at or near the end of the web which is in process of formation upon the opposite bed, this action being repeated at each end of the web during one complete reciprocation of the carriage. I have found, however, that where two yarns are employed, as is the case in knitting two distinct webs of this character, the union of said webs can be effected without interknitting wherever the change from one yarn to the other takes place. In the machine described in my said Patent No. 582,547 this change of yarn is effected by causing the traveling carriage to drop one yarn and pick up the other at the termination of a complete reciprocation, and heretofore the two yarns have been entirely isolated from one another. At the momen

of such exchange I now throw the yarn which has just been supplied to one row of the needles across the yarn which is about to be supplied to those of the other row, and thus intertwine the two yarns at the point from which the carriage starts. This intertwining of the two yarns unites the two webs without interknitting them, the line of union possessing a beautiful finish and being much less conspicuous than that formed by actual interknitting, while it is fully complete in all structural characteristics. In the machine described in my said Patent No. 582,547 the exchange of yarns occurs only at one end of the needle-bed, and the intertwining is only effected thereon after a complete reciprocation of the needle-carriage back and forth. When, therefore, that machine is used in its present form, the intertwining of the yarns can only be employed to join the webs along one line of their proximate edges, the uniting of the web along the other line being preferably effected by interknitting in the manner described in my said application, Serial No. 713,891. When this method of operation has been carried on during the period desired for the formation of the composite web—say, for instance, throughout the foot and heel portions of the stocking—the transition is made to the alternative method of operation whereby instead of forming two independent webs and uniting them along their proximate edges a single and uniformly-continuous tubular web is knit throughout the leg portion. I do not, however, in this application claim the mechanism or process by which the above-stated results are accomplished, nor do I limit myself to the use of the machinery above referred to, as I have merely selected the same to indicate a typical method of production. The stocking which constitutes my present invention may be made upon any type of knitting-machine which is capable of producing two independent webs with proximate edges and a continuous tubular web and which is also capable of employing two yarns and changing from one to the other either at one or both limits of the independently-knit webs.

Referring now to Fig. 1, which shows a stocking formed in accordance with my invention, A indicates the leg portion of the stocking, and B the foot portion thereof, the latter having the usual heel and toe pockets C D, respectively. The toe and bottom portion of the foot are represented as being formed of white yarn, while the upper portion of the foot and the whole of the leg are represented as formed of shaded yarn.

In Fig. 2 the line of union between the two independently-knit webs F and G is shown, where it will be seen that the yarn f of the loops which compose the web F is intertwined with the yarn g of the loops which compose the web G by merely crossing the same.

Referring now to Fig. 3, which represents the line of union between the other edges of the independently-knit webs, it will there be seen that the yarn f' of the web F' is interknit with the yarn g' of the web G', such interknitting being indicated as extending from the bottom of the web up to the point I, above which the fabric is represented as being formed in a continuous and uniformly-knit tube instead of by the interknitting of separate webs. Such a change from the two webs to the single one of course occurs at the termination of the other line of union; but I do not deem it necessary to illustrate this in both of the enlarged views.

As before stated, the fact that the union is effected by intertwining at one side only of the independently-knit webs is due to the limitations of the machine which I have referred to; but obviously the fabric itself is not essentially thus limited. Hence I mean by the language which I employ in my claims to include such stocking whether the independently-knit webs be united along both pairs of their proximate edges or only along one pair thereof, the conspicuous feature of my invention residing in the fact that such a union can be effected without the action of the needles as distinguished from the interknitting of the webs by the direct action of the needles.

I use the term "intertwined" as a convenient one to comprehend, broadly, the relation of two or more yarns which are definitely engaged in such a fabric by any other means than the knitting action of a needle.

Having thus described my invention, I claim—

1. In a stocking, the combination of a foot portion, comprising two independently-knit webs, united by intertwined yarns, and a leg portion of single, continuous, tubular-knit web, substantially as set forth.

2. In a stocking, the combination of a foot portion, comprising two independently-knit webs having a pair of their proximate edges united by intertwined yarns, and having the other pair of said edges united by interknit loops, and a leg portion of single, continuous, tubular-knit web, substantially as set forth.

JOHN G. POWELL.
